UNITED STATES PATENT OFFICE

160,196

STEREOSCOPIC VIEWER

Charles M. Pettingell, Meadville, Pa., assignor to
Keystone View Company, Meadville, Pa., a cor-
poration of Pennsylvania

Application May 20, 1950, Serial No. 10,066

Term of patent 14 years

(Cl. D61—1)

To all whom it may concern:

Be it known that I, Charles M. Pettingell, a citizen of the United States, residing at Meadville, in the county of Crawford and State of Pennsylvania, have invented a new, original, and ornamental Design for Stereoscopic Viewer, of which the following is a specification, reference being had to the accompanying drawing, forming part thereof.

Fig. 1 is a plan view of a stereoscopic viewer, showing my new design.

Fig. 2 is a side view thereof.

Fig. 3 is a front view; and

Fig. 4 is a rear view of the same.

Parts of the drawings are lined to indicate contrasting colors.

I claim:

The ornamental design for a stereoscopic viewer, as shown.

CHARLES M. PETTINGELL.
